UNITED STATES PATENT OFFICE.

ARCHIE F. NAIR AND HOBERT A. NAIR, OF GLENDALE, CALIFORNIA.

GAS BOMB ADAPTED TO BE DISCHARGED FROM AIRCRAFT.

Original application filed July 29, 1927, Serial No. 209,596. Divided and this application filed May 9, 1928.
Serial No. 276,397.

Our invention relates to a novel gas bomb adapted for discharge from aircraft and which will function in the novel manner hereinafter described.

5 We attain the objects of our invention by the means disclosed in the accompanying drawings, in which,—

Figure 1 is a side elevation of our invention;

10 Fig. 2 is a longitudinal section through same on line 2—2 of Fig. 1;

Fig. 3 is an end elevation of the bomb; and

Fig. 4 is a section on line 4—4 of Fig. 2.

15 Like numerals designate like parts in each of the several views.

Referring to Figs. 2 and 4, we provide the main torpedo 13. We also provide a poison gas chamber 23 in contact with which is a 20 percussion member 20. In contact with this member 20 is a firing pin 21 carried by the slideable firing bolt 16, which bolt carries a bolt head 25 preferably of the shape shown in Fig. 2 and which will function to operate the device, discharge the bomb, and release the gas if the device is dropped from aircraft onto the ground. We also provide a detachable cap 17 near the end of the poison gas chamber to permit of filling the bomb 25 with gas. The end cap or cover 22 of the main torpedo 13 is held in place by lock bar 19 which in turn is releasably engaged by the spring hooks 18, the ends of which are fastened to the outer walls of the main torpedo by any suitable means, such as the rivets 26.

The device may be operated either as a bomb to be destroyed by contact of the head of the firing bolt with any object when the bomb is dropped from aircraft or it may be utilized as a time bomb to be discharged at a pre-determined time after being disposed in a desired location, depending on the length of time the time device 15 requires to function.

It is one of the purposes of our invention to provide a type of bomb which, when dis-

charged, will effectually destroy itself so that no one may learn how it is made.

This application is a division of Serial 50 209,596, filed July 29, 1927.

What we claim is—

1. As a new article of manufacture for use in a device of the class described, a bomb comprising a gas chamber having means to permit filling the bomb with gas, a main explosive torpedo affixed to the gas chamber, a percussion member supported in fixed position to the gas chamber, a firing pin and bolt positioned to fire the percussion member such as would result from the bomb falling to the ground from aircraft, a detachably mounted head releasably hooked in place on the main torpedo chamber. 60

2. As a new article of manufacture for use in a device of the class described, a bomb comprising a gas chamber having means to permit of filling the bomb with gas, a main explosive torpedo affixed to the gas chamber, a percussion member supported in fixed position to the gas chamber, a firing pin and bolt positioned to fire the percussion member such as would result from the bomb falling to the ground from aircraft, and an end cap releasably hooked in place on the main 70 torpedo chamber. 75

3. As a new article of manufacture for use in a device of the class described, a bomb comprising a gas chamber having means to permit of filling the bomb with gas, said chamber being of substantially frustro-conical shape, a main explosive torpedo affixed to the gas chamber, a percussion member supported in fixed position to the gas chamber, a firing pin and bolt positioned to fire the percussion member such as would result from the bomb falling to the ground from aircraft, an end cap releasably hooked in place on the main torpedo chamber, and a time fuse operatively connected with the 80 bomb, whereby to permit of utilizing the device either as a time bomb or otherwise. 90
